JAMES J. FLINT, OF DENVER, COLORADO.

GASOLENE-LAMP.

SPECIFICATION forming part of Letters Patent No. 732,686, dated June 30, 1903.

Application filed April 12, 1902. Serial No. 102,671. (No model.)

To all whom it may concern:

Be it known that I, JAMES J. FLINT, a citizen of the United States of America, residing at Denver, in the county of Arapahoe and State of Colorado, have invented certain new and useful Improvements in Gasolene-Lamps; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to improvements in gasolene-lamps; and it consists of the features, arrangements, and combinations hereinafter described and claimed, all of which will be fully understood by reference to the accompanying drawings, in which is illustrated an embodiment thereof.

In the drawings, Figure 1 is a side elevation of the lamp, partly in section. Fig. 2 is a section taken through the generator and a portion of the lamp-frame, shown on a larger scale. Fig. 3 is a similar view illustrating a modified form of construction. Fig. 4 is an enlarged fragmentary section taken through the reservoir. Fig. 5 is a fragmentary section taken through the lamp-frame, illustrating the shut-off valve. Fig. 6 is a section taken through the central tube connecting the two parts of the reservoir. Fig. 7 is a detail sectional view, on a larger scale, showing the screw-plug and valve construction illustrated in Fig. 4.

The same reference characters indicate the same parts in all the views.

Let the numeral 5 designate the reservoir, which is composed of two semispherical members 5^a and 5^c, connected by a central vertical tube 6, whose extremities are threaded to receive nuts 7 and 8, respectively. The nut 7, applied to the lower extremity of the tube, is countersunk in the bottom of the reservoir, while the nut 8 protrudes at the top and is exteriorly threaded to receive a cast bracket 9, which is screwed thereon. A burner 10 is mounted on this bracket and communicates with a passage 12, leading from a tube 13, forming a part of the lamp-frame. A passage 14 in this bracket communicates at one

extremity with a tube 15 of the lamp-frame located on the opposite side of the burner from the tube 13, making the lamp symmetrical. A shut-off valve 16 is screwed into a casting 17, interposed between the parts of the frame-tube 15. This casting is provided with an irregular passage 17^a, which may be opened and closed at pleasure by turning the valve-stem, whereby the gasolene may be cut off from or allowed free passage to the generator, as may be desired.

The upper extremity 15^b of the frame-tube 15 is made heavier than the body of the tube and provided with a threaded opening, into which is screwed a nipple 18, applied to or formed integral with one extremity of the generator-tube 19. This nipple is interiorly threaded to receive the threaded portion of a valve-rod 20 of the generator. The upper extremity of the tube 15 is also provided with a projection 15^a, bored to communicate with the tube and forming a guide for the rod 20, which passes through a stuffing-box 21, applied to the said projection. The threaded portion of the rod 20 is provided with a groove 20^a, through which the gasolene passes from the frame-tube 15 to the generator-tube, in which is located a needle 22 of the valve-rod. The tube 19 is located directly above the burner and the exit extremity thereof, where the gas escapes discharges into an air-bell 23, mounted on and located directly in front of the open upper end of the frame-tube 13. This bell is formed larger than the tube 13 to permit air to mix freely with the gas in the said tube, whereby the gas is supplied with the necessary oxygen for illuminating purposes before passing to the burner.

Connected with the upper extremities of the tubes 13 and 15 is a hanger 24, provided at its upper extremity with a suspension-hook 25.

The reservoir-tube 6 is provided with a wire-gauze or other suitable packing 6^c, forming a strainer for the gasolene, which passes to the tube through an opening 6^a, formed in the lower portion of said tube.

Inserted in an opening formed in the member 5^c of the reservoir is a filling-tube 26. The outer extremity of this tube is normally closed by a screw-plug 27, provided with a valve 28, adapted to be connected with an

air-pump (not shown) for the purpose of compressing the air within the reservoir above the gasoline, whereby the latter is forced through the opening 6^a into the tube 6 and 5 thence up through the packing therein, where the liquid is relieved of its impurities, and thence through the passage 14 and up through the frame-tube 15 to the generator, where it is heated and converted into gas while passing through the generator-tube by the flame from the burner below. The gas generated in the tube escapes to the air-mixing bell 23 and passes thence downwardly through the frame-tube 13 and through the passage 12 to 10 the burner, which is equipped with a Welsbach mantel.

In the construction shown in Fig. 3 the generator 19^a is formed heavier than the corresponding element shown in Fig. 2, and a 15 reduced tube 19^c is screwed thereinto.

While, as shown in the drawings, the air-bell is mounted on the upper extremity of the frame-tube 13, it may be mounted on the adjacent extremity of the generator-tube with 20 equally good results. Hence I do not limit the invention to any especial manner of mounting the air-bell.

The inner extremity of the valve 28 is cone-shaped or beveled to fit a seat of corresponding shape in the plug 27. Above the bevel or outside of the latter the valve is reduced, as shown at 28^a, and a passage-way 28^c through the valve terminates at such reduced portion, whereby when the valve is seated communication with the reservoir by way of the passage-way 27 in the screw-plug is cut off. As soon, however, as the valve is moved outwardly from its seat air may be forced into the reservoir by connecting the nipple of an 35 air-pump with the screw-threaded socket 28^a at the outer extremity of the passage 28^c of the valve.

Having thus described my invention, what I claim is—

1. In a gasoline-lamp, the combination with a lamp-frame, of a reservoir composed of two parts, a central tube connecting the two parts, nuts applied to the tube extremities for fastening the said parts together, the tube having an opening communicating with the reservoir below the liquid, and its upper extremity being open to allow the liquid to pass to the lamp-generator, substantially as described.

2. In a gasoline-lamp, the combination with a lamp-frame, of a reservoir composed of two semispherical parts, having protruding overlapping beads, a vertical connecting-tube passing through the center of the reservoir, nuts applied to its extremities and screwed down on the reservoir parts, whereby they are securely held in place, the lower portion of the tube having an opening for the entrance of the gasoline, the tube being also provided with a strainer-filling, and its upper portion being open to allow the gasoline under pressure to pass to the generator.

3. In a gasoline-lamp, the combination with

a reservoir composed of two semispherical parts, of a vertical tube passing through the center of the reservoir, and having an opening below the liquid to allow it to enter, the upper extremity of the tube being open, nuts applied to the extremities of the tube for holding the two parts of the reservoir together, a casting applied to the upper extremity of the tube and having a gasoline-passage in communication with the tube, a frame-tube communicating at one extremity with said passage, a generator-tube connected with the other extremity of the frame-tube, a valve-rod journaled in the upper extremity of the frame-tube and having a needle located in the generator-tube. 70 75 80

4. In a gasoline-lamp, the combination with a reservoir composed of two semispherical parts, of a vertical tube passing through the center thereof, nuts applied to the extremities of the tube for holding the two parts of the reservoir together and having an opening below the liquid for the entrance of the gasoline to the tube whose upper extremity is open, a bracket applied to the upper extremity of the said tube and having two separated passages, one for the gas to the burner and the other for the gasoline to the generator, a frame-tube whose lower extremity communicates with the last-named passage, a nipple screwed into the upper extremity of the frame-tube, a valve-rod journaled in the frame-tube and threaded in the said nipple, a generator-tube connected with the nipple, the valve-rod having a passage for the gasoline from the frame-tube to the gasoline-tube, a needle connected with the valve-rod and located in the generator-tube, another frame-tube forming a conduit for the gas to the burner, and an air-bell mounted on the upper extremity of said tube to receive the gas from the generator. 90 95 100 105

5. In a gasoline-lamp, the combination of a reservoir having a vertical tube passing through its central portion and provided with an opening below the liquid for the entrance of the gasoline, the upper extremity of the tube being open, a bracket applied to the upper extremity of the tube and having a passage for the gasoline to the generator, a frame-tube whose lower extremity communicates with said passage, a shut-off valve located in the frame-tube between the reservoir and the generator, a nipple screwed into the upper extremity of the frame, a generator-tube applied to said nipple, a valve-rod journaled in the frame-tube and having an inlet located in the generator-tube, the valve-rod being threaded in the nipple, its threaded portion having a groove forming a passage for the gasoline from the frame-tube to the generator-tube, another open-ended frame-tube whose upper extremity is located in front of the exit extremity of the generator-tube, and an air-bell mounted on the upper extremity of the last-named frame-tube which forms a conduit for the gas, the lower extremity of 110 115 120 125 130

the gas-tube being connected with the said bracket which is provided with a gas-passage to the burner.

6. In a gasolene-lamp, the combination with 5 a reservoir, of a filling-tube inserted therein, a screw-plug inserted in the filling-tube, a valve screwed into said tube and adapted to receive the nipple of an air-pump, a central tube located in the reservoir and having 10 an inlet-opening below the liquid, the upper extremity of the tube being open, a bracket applied to the upper extremity of the tube and having two separated passages, one communicating with the reservoir-tube, 15 a frame-tube whose lower extremity communicates with the last-named passage, a nipple threaded in the upper extremity of the frame-tube, a valve-rod journaled in the frame-tube and threaded in the nipple, its 20 threaded portion having a groove forming a passage for the gasolene to the generator-tube, a generator-tube connected with the nipple, an inlet connected with the valve-rod and located in the generator-tube, another 25 frame-tube whose upper extremity is located directly in front of the gas-escape opening of the generator-tube, and forming a gas-conduit, an air-bell mounted on the upper extremity of the gas-tube, the lower extremity 30 of the last-named tube communicating with a bracket-passage which leads to the burner, substantially as described.

7. In a gasolene-lamp, the combination with a reservoir composed of two semispherical parts, of a vertical tube passing through the center thereof connecting the two parts and having an opening below the liquid for the entrance of the gasolene to the tube whose upper extremity is open, fastening means applied to the tube extremities for securing the reservoir parts in place, a bracket applied to the upper extremity of the said tube and having two separated passages, one for the gas to the burner and the other for the gasolene to the generator, a frame-tube whose lower 40 extremity communicates with the last-named passage, a generator-tube connected with the other extremity of the frame-tube, a valve-rod journaled in the upper extremity of the frame-tube and having a needle located in 45 the generator-tube, another frame-tube whose upper extremity is located directly in front of the gas-escape extremity of the generator-tube, and an air-bell interposed between the upper extremity of the last-named frame-tube 50 and the gas-escape extremity of the generator-tube.

In testimony whereof I affix my signature in presence of two witnesses.
